UNITED STATES PATENT OFFICE.

HEINRICH REPENNING, OF AIX-LA-CHAPELLE, GERMANY.

RAISING-GIG FOR LONGITUDINAL AND TRANSVERSE TEAZELING.

1,173,608.

Specification of Letters Patent. Patented Feb. 29, 1916.

Application filed February 24, 1915. Serial No. 10,262.

To all whom it may concern:

Be it known that I, HEINRICH REPENNING, a subject of the King of Prussia, and resident of Aix-la-Chapelle, in the Kingdom of Prussia, Empire of Germany, professor, have invented certain new and useful Improvements in Raising-Gigs for Longitudinal and Transverse Teazelng, of which the following is a specification.

10 Since the first teazel-drum composed of rotary teazels appeared, it has undergone changes chiefly consisting in interposing fixed teazel-rods armed with card-clothing, or brush-rods, between said rotary teazels 15 in such a manner that every rotary teazel, or a plurality of such teazels, is or are followed by a teazel-rod, or by a brush-rod. The object of such interposition being, to range and to teazel the nap raised by said 20 rotary teazels. Besides this raising-gigs are known, wherein rotary teazels, or teazel-rods, are arranged to execute lateral movements, *i. e.*, in the direction of their axis. The teeth of the card-clothing of such 25 rotary-teazels, or of such teazel-rods, are directed sidewise, so that the points of said teeth execute a transverse teazelng-action upon the warp-threads on account of the axial movements of said teazel-organs. It is 30 evident that for reasons of the combined motions of the cloth on the one hand, and of said rotary teazels, or of said teazel-rods, on the other hand, the teeth of these teazel-organs cannot strike the warp-threads 35 right angles but under an acute angle only.

The object of my present invention is to produce a raising-gig for simultaneously performing the longitudinal as well as the transverse or cross teazelng. To this end I 40 combine in the same teazel-drum fixed rotary teazels and reciprocating teazel-devices in such a manner, as to obtain a new, hitherto unknown teazelng-process. To assure the latter, the reciprocating teazel-devices are 45 made to act upon the warp-threads only, whereas the fixed rotary teazels are made to exert their influence not only upon the weft-threads but also upon the warp-threads, as will be more fully explained below.

50 In the accompanying drawing:—Figure 1 is a longitudinal sectional view of a raising-gig embodying my invention, taken on line A—B of Fig. 2; Fig. 2 is a partial cross sectional view taken on line C—D of Fig. 1, whereas Fig. 3 is a similar view taken on 55 line E—F of the same figure; Fig. 4 is a

longitudinal sectional view similar to Fig. 1 of a modification of my invention; Fig. 5 is a partial cross sectional view taken on line G—H of Fig. 4; Figs. 6 and 7 are enlarged sectional detail views; Fig. 8 is a longitudinal sectional view of another modification of my invention, and Figs. 9 and 10 are partial cross sectional views taken on lines I—K and L—M of Fig. 8 respectively; 60 Figs. 11 and 12 represent details of a reciprocating teazel-device.

In the frame 1 is journaled the driving-shaft 2 of a teazel-drum 3 composed of rotary teazels 4 and of reciprocating teazel-devices 5. The latter are in this instance of cylindrical shape and can execute rotary as well as reciprocating movements. The rotary teazels 4 and said teazel-devices 5 are journaled in the drum-heads 6 and 7 (Fig. 70 75 1). To rotate the fixed rotary teazels 4 with a greater circumferential velocity than the rotatable reciprocating teazel-devices 5, each rotary teazel is provided with a pinion 8 that meshes with a wheel-rim 9 attached 80 to a spur-wheel 10 which cooperates with the larger pinions 11 of said teazel-devices 5. These pinions 11 are slidingly seated upon the shaft 22 of said teazel-devices by means of a feather-key and are held against axial 85 displacement by their hubs, as indicated in Fig. 1.

The wheel 10 is provided with a sleeved hub 10', which freely rotates upon the driving-shaft 2 and carries a step-pulley 13 to 90 vary the circumferential speed of the active members 4 and 5 of the teazel-drum 3, if deemed necessary. The teazel-devices 5 are preferably arranged in two groups to simplify their reciprocation. To compulsorily 95 produce the latter I employ a double-eccentric 14 the sheaves of which are set at an angle of 180° to each other and connected with a spur-wheel 15 revolvably mounted upon the driving-shaft 2. Said spur-wheel 100 meshes with a pinion 16 secured to a shaft 17, which is driven by a pulley 18. To each eccentric-strap 19 four links 20 are attached, the free ends of which being linked to bell-crank 21 pivotally supported in the drum-head 6. The longer arms of these bell-crank 21 are forked to straddle the shafts 12 of the reciprocating teazel-devices 5 between the shaft-collars 23, as indicated in Figs. 1 and 2. Since the cloth (not shown) on 105 which a nap has to be raised is drawn across the teazel-drum at right angles to the axis

of the latter, the teeth 4' of the card-clothing of the rotary teazels 4 are operating in planes crossing the axis of rotation of these teazels at right angles. The teeth 5' of the card-clothing of the rotatable reciprocating teazel-devices 5 must however be arranged to meet the conditions arising from the combined reciprocating and rotary motions of these devices. The path described by these teeth will therefore be shaped more or less sinuously. Any card-clothing with teeth adapted for raising a nap on woolen goods, etc., may be employed, provided their teeth are properly directed. To aid the cloth in retaining its true course of travel notwithstanding the lateral action of the reciprocating teazel-devices 5 it is advisable to let the teeth 5' of one group of said teazel-devices point in one direction and the teeth of the other group in the opposite direction, as will be apparent from comparing Fig. 1 with Figs. 4 and 6.

The operation of my raising-gig is as follows:—After the teazel-drum 3 and with it the rotary teazels 4 and the reciprocating teazel-devices 5, alternately arranged therein, have been set in rotation, the wheel 9, 10 and the double-eccentric 14 will be set in motion. In passing the cloth the teeth 4' of the rotary teazels 4 will pick only the weft-threads thereof, which action represents the longitudinal teazelng, because carried out lengthwise of said cloth. This picking of the weft-threads by the teeth 4' can at the present state of technics be regulated to an extremely fine degree of exactness. To let the warp-threads undergo a similar teazelng action by the teeth 5' of the reciprocating teazel-devices 5, the card-clothing of the latter is selected with a view to let the teeth thereof, on passing transversally or crosswise over the cloth, push the hair or fibers of the warp-threads out of their path, crossing that of the teeth 5', into the path of the teeth 4' of the rotary teazels 4 and thus enable the latter to engage with and exert a teazelng action upon said hair or fibers also. In this peculiar manner it is made possible for the teeth of the rotary teazels 4 to exert a teazelng action upon the weft-threads as well as upon the warp-threads. The work performed by the teeth 5' of the reciprocating teazel-devices 5 to bring about this result represents the transverse teazelng, because carried out transversally or crosswise on said cloth. It is of course necessary to arm the teazel-devices 5 with teeth 5' sufficiently sharp to pick and teazel the warp-threads directly.

60 Instead of employing eccentrics and bell-cranks for reciprocating the teazel-devices 5 a cam 24 may be used, the periphery of which being provided with a sinuously shaped groove 25 adapted to receive guide-pins 26 which are rotatably mounted upon

the shaft 12 of the reciprocated teazel-devices 5 and preferably armed with an anti-friction element 28. Each guide-pin 26 is protected against jamming and tilting in the groove 25 by a broad guide-plate 29 kept in 70 sliding contact with the periphery of said cam. Rotary motion may also be imparted to the teazels 4 and the teazel-devices 5 by belt-gearing instead of wheels and pinions. Figs. 4 and 5 show how a belt 30 may be 75 arranged to transfer motion from the driving pulley 31 to the pulleys 32 and 33 of the drum-members 4 and 5 respectively. It is of course possible to employ stationary eccentrics and cams for reciprocating the 80 teazel-devices 5 or to reduce their rotary motion to a very limited degree. Since the teazelng action of the reciprocating teazel-devices 5 depends on the speed of said eccentrics, or of said cam, the pulley 18 might be 85 replaced by a step-pulley, or braking-devices might be employed instead. In a similar manner the circumferential velocity of the rotary-teazels 4 and that of the reciprocating teazel-devices 5 may be regulated. 90

Figs. 8 to 12 show another modification of my invention, wherein the rotatable reciprocating teazel-devices 5 of Figs. 1 to 7 inclusive are replaced by reciprocating rod-shaped teazel-devices 34. The same means employed for reciprocating the teazel-devices 5 may be used for actuating these rod-shaped teazel-devices steadied by tail-rods 35 guided in the drum-head 7. The rotary teazels 4 of this modification may be rotated by any of the means suitable for this purpose and already described in connection with Figs. 1 and 4. These reciprocating teazel-rods are arranged in two sets like the cylindrical reciprocating teazel-devices 105 in Figs. 1 and 4 and are, like these, provided with card-clothing of which the teeth 34' of the one set are arranged in opposition to the teeth of the other set, as will be apparent on comparing Figs. 8 and 11. 110

The reciprocating teazel-devices transfer during their back-stroke any fibrous material gathered on their working-stroke to the cloth from which it is removed by the rotary teazels 4 to be finally carried off by a cleaning-device (not shown) arranged beneath said teazel-drum.

I claim:—

1. A raising-gig of the character described, comprising a drum, a plurality of first teazels journaled therein, means for imparting a rotary motion only, to said first teazels, a plurality of second teazels likewise journaled in the drum and interposed between the first teazels, and means for imparting a combined reciprocative and rotary movement to the second teazels. 125

2. A raising-gig of the character described, comprising, in combination, a teazel-drum containing rotary teazels adapted 130

for longitudinal teazelng and stationarily journaled in said drum, and teazel-devices adapted for transverse teazelng and reciprocatingly mounted in said drum; means 5 for rotating said rotary teazels independent of the rotation of said teazel-drum, and means for reciprocating said teazel-devices with variable speed.

3. A raising-gig of the character described, comprising, in combination, a teazel-drum composed of a plurality of reciprocating teazel-means having teeth adapted to gather fibrous elements from the warp-threads and range them crosswise to said 15 threads in the direction of the working-stroke of said reciprocating teazel-means, and of a plurality of fixed rotary teazel-means provided with teeth adapted to pick the weft-threads and to subject said fibrous 20 elements of the warp-threads to renewed teazelng actions; means for imparting the said reciprocating action to the first-named teazel-means while said teazel-drum is being rotated, and means to impart variable rotary motion to said rotary teazel-means independent of the rotation of said teazel-drum.

4. A raising-gig of the character described, comprising, in combination, a teazel-drum containing rotary teazels adapted to subject the weft-threads to a teazelng-action, and rotatable reciprocating teazel-devices alternately arranged with said rotary teazels in said teazel-drum and adapted to subject the warp-threads to a teazelng-action; means for simultaneously rotating said rotary teazels and said rotatable reciprocating teazel-devices around their own axis independent of the rotation of said 35 40 teazel-drum, and means for imparting to said rotatable reciprocating teazel-devices a reciprocating motion while being rotated around their own axis and that of said teazel-drum.

45 5. A raising-gig of the character de-

scribed, comprising, in combination, a teazel-drum containing fixed rotary teazels for longitudinal teazelng having teeth operating in planes crossing the axis of rotation of said rotary teazels and of said teazel-drum, and rotatable reciprocating teazel-devices for transverse teazelng provided with teeth moving on helical paths lengthwise to the axis of rotation of the teazel-devices carrying them; means for rotating 55 said rotary teazels and said rotatable reciprocating teazel-devices around their own axis with different circumferential velocities independent of the rotation of said teazel-drum, and means for imparting to the 60 rotatable reciprocating teazel-devices a reciprocating motion in addition to their rotary motion.

6. A raising-gig of the character described, comprising a drum, a plurality of 65 first teazels journaled therein, means for rotating said teazels around their axis independent of the rotation of the teazel-drum, a plurality of second teazels likewise journaled in the drum and interposed between 70 the first teazels, and means for reciprocating the second teazels independent of the rotation of the drum.

7. In a raising-gig of the character described, a teazel-drum consisting of a series 75 of fixed rotary teazels adapted for longitudinal teazelng, and of a series of reciprocating teazel-devices adapted for transverse teazelng, of which last-named series a part is provided with teeth pointing in one direction and of which same series the remainder is armed with teeth pointing in the opposite direction.

Signed by me at Aix-la-Chapelle, Germany, at this 5th day of February, 1915.

HEINRICH REPENNING.
